UNITED STATES PATENT OFFICE.

CHARLES AMOS FORSYTH, OF ATLANTA, GEORGIA.

SIGN.

Application filed September 21, 1925. Serial No. 57,770.

The present invention relates to signs, and more particularly to that type adapted to be illuminated and to be suspended from a building or other suitable support.

5 An object of the present invention is to provide a sign which is adapted for quick attachment and detachment to and from a support, such as the wall of a house or the like, and which when attached may be securely locked in position from unauthorized removal, and a sign which when attached to a house or the like may be illuminated from a convenient lamp socket, such as found on porches, or in adjacent portions of the

15 house.

Another object of the invention is to provide a sign which may be economically constructed from a single blank so peculiarly folded and bent as to provide a signboard 20 and reflector for supporting the lamp and reflecting the rays thereof against the signboard.

The invention is primarily for the use of realtors or the like who have control over the 25 renting or selling of a number of pieces of property and upon which may be placed, permanently, supporting devices to which the sign may be easily and quickly attached, and from which the sign may be easily and 30 quickly removed. By the use of this sign a number of the same may be maintained in use by exchanging them from one building to another. The sign, however, is adapted to individual and other uses.

35 The above and various other objects and advantages of this invention will be in part described and in part understood from the following detail description of the present preferred embodiment, the same being illustrated in the accompanying drawings, wherein:

Fig. 1 is a perspective view of a sign constructed according to the present invention and in position against a wall;

40 Fig. 2 is a plan view of a blank from which the sign is constructed;

Fig. 3 is a front elevation of the sign in its complete form;

Fig. 4 is a fragmentarily enlarged end elevation of the sign showing an electric lamp mounted therein;

Fig. 5 is a top plan view of the sign;

Fig. 6 is a front elevation of the sign as applied to the front door of a building, 55 showing the electric cord leading into the

sign from a suitable source of electric energy; and

Fig. 7 is a fragmentary sectional view through a portion of the reflector and frame part of the sign.

Referring to the drawings, 10 designates a signboard preferably constructed of metal and comprising the lower part of a blank as shown in Fig. 2. The signboard 10 is preferably flat and adapted to receive suitable data tested for display which may be painted, pasted or otherwise suitably secured to the signboard. The upper part of the blank provides a reflector 11 which is substantially of the same width as the signboard 10 and which is bent outwardly at right angles to the upper edge portion 12 of the sign board and curved downwardly therefrom as shown in Fig. 4. The outer end of the reflector 11 is spaced forwardly 75 of the upper part of the sign board 10 and provides a hood or casing in which is housed and protected a lamp socket 13 secured against the inner side of the reflector 11 and which carries a lamp 14. The lamp socket 80 13 is provided with an electric cord 15 which may be carried outwardly through the reflector 11 to any suitable source of electric current for supplying energy to the lamp 14.

The blank is provided with a pair of outwardly extending arms 16 which project in an edgewise direction from the blank above the top edge 12 of the signboard and which are bent upwardly as shown in Fig. 3 to support the sign. These arms 16 are provided with apertures 17 therein through which is detachably threaded a cross bar or rod 18 having a head 19 on one end and an eye piece 20 on its other end. The head 19 holds the rod 18 from movement in one 95 direction through the openings 17, while the eye piece 20 is flat and adapted to pass freely through the openings 17 and is also adapted to receive a padlock 21 or the like for holding the rod 18 from unauthorized 100 removal.

The outer end of the reflector 11 is provided with a frame 22 which comprises the upper edge portion of the blank turned over thereon on the line 23. The upper edge 105 portion 22 extends beyond the edges of the blank to provide a pair of frame bars 24 which are adapted to be bent inwardly at substantially right angles to the outer end of the reflector 11 and which have inturned 110

flanges 25 at their extremities bent over upon the lines 26 to lie flat against the signboard 10. Rivets 27 secure the flanges 25 to the signboard and thus provide a rigid 5 frame structure between the signboard and the lower end of the reflector 11.

In order to removably support the sign, a pair of screw eyes 28 are provided having shanks 29 of any suitable form for permanent attachment to a wall 30 or the like, the screw eyes 28 being permanently mounted and adapted to remain in place after the sign has been removed.

In use, the screw eyes 28 are permanently 15 mounted upon a door, a wall or other desired support. The sign is attached to the screw eyes by passing the eye piece 20 through one of the upstanding arms 16 of the sign, and then threading the rod 18 20 through the eye pieces 28 and through the opposite arms 16. The padlock 21 may now be applied if desired, and the sign is thus secured in position against the support. The electric cord 15 is connected to a suitable 25 socket 31 or the like from which current may be taken for operating the lamp 14. The rays from the lamp 14 are deflected by the reflector 11 downwardly upon the body of the signboard 10 so as to illuminate the same and clearly display the 30 data or the like which is placed on the signboard. Where the sign is used to advertise the rental of a property, and it is desired to remove the sign, it is only necessary to 35 detach the cord 15 and remove the rod 18 from the screw eyes 28 when the sign may then be conveyed to a different support and suspended thereon as above outlined.

The entire sign comprises but a single 40 blank of sheet metal or the like so peculiarly bent and shaped as to provide a rigid structure

easily formed. The electric lamp 14 and its parts, and the rod 18 are the only additional parts required for the complete sign.

It is, of course, understood that various changes and modifications may be made in the details of construction and design of the above specifically described embodiment of this invention without departing from 50 the spirit thereof, and being limited only by the scope of the following claims.

What is claimed is:—

1. A sign comprising a signboard, a reflector mounting on said signboard and extending outwardly and downwardly therefrom, a brace connecting the opposite lower ends of said reflector and the signboard, said brace being integral with said reflector, said reflector being integral with said signboard, 60 illuminating means mounted in the reflector, upstanding arms on said reflector and at the upper opposite ends thereof, and a suspension rod carried through said arms.

2. A sign comprising a flat signboard, a 65 forwardly and downwardly curved reflector connected to the upper end of the signboard and provided with a pair of upstanding arms at its opposite edges, the lower edge portion of the reflector being returned 70 against the inner side thereof to provide a reinforcing frame and said lower edge portion having frame bars extending from opposite ends thereof and bent inwardly and secured to the signboard for bracing 75 the reflector thereon, a removable rod secured through said arms, and permanently attachable supporting members having eye portions for removably receiving said rod therethrough.

CHARLES AMOS FORSYTH.
